UNITED STATES PATENT OFFICE.

CHARLES J. DORSEY, OF BALTIMORE, MARYLAND, ASSIGNOR TO HENRY S. DULANEY, OF BALTIMORE, MARYLAND.

HORSESHOE GAME-BOARD.

SPECIFICATION forming part of Letters Patent No. 711,483, dated October 21, 1902.

Application filed February 21, 1902. Serial No. 95,104. (No model.)

To all whom it may concern:

Be it known that I, CHARLES J. DORSEY, a resident of Baltimore, in the State of Maryland, have invented certain new and useful 5 Improvements in Horseshoe Game-Boards; and I do hereby declare the following to be a full, clear, and exact description of the invention, such as will enable others skilled in the art to which it pertains to make and use 10 the same:

This invention relates to game-boards of the class having a way or track along which a ball may be propelled and seats in either of which the ball may come to rest.

15 In the accompanying drawings, Figure 1 is a plan view of the game-board. Fig. 2 is a vertical section of said board on line 2 2 of Fig. 1. Fig. 3 is a section of board on the line 3 3 of Fig. 1.

20 The numeral 1 indicates a board of suitable dimensions and shape, to which is secured a rim 2, which is of substantially horseshoe shape. Centrally within the said rim is secured to the board a large horseshoe-shaped

25 body 3, which, with rim 2, forms a horseshoe-shaped way or track 4. The bottom of said way is preferably made to incline downward toward the side of the shoe-shaped body 3, which rests against the board 1, and at suitable intervals, preferably in the sides of the shoe under the lugs 5, which indicate horseshoe-nail heads, are openings 6, and in the

30 toe of the shoe is an opening 6', preferably larger than openings 6. The way 4 also has small up and down grades, the parts marked 35 17 being the highs, and the parts marked 18 being the lows, of the inclines. Opposite opening 6' about the middle of the way 4 is a pin 19', between which and the rim is room for

40 the ball to pass. If the ball goes to the other side of the pin, it will be driven into and through opening 6'. At one end of the way 4 is a spring 7, supported at 8, the free end of which spring has 45 a handle 9, which may be guided in the slot 10 at one end of the shoe 3. To spring 7 is connected a small horseshoe 11, held by nails or screws 12 in elongated slots 13. Under the shoe is a depression 14, in which before 50 each play rests a ball or marble 15 between the sides of the shoe.

In the board within shoe 3 is an outer series (horseshoe shape) of depressions 16, also an inner series of depressions 17 of like shape, and a central depression 18 within a small 55 horseshoe 19, the ends of which are far enough apart to admit the ball. Depression 18 is given a counting value equal to the limit of the game—say five hundred—so that a player who first gets the ball into the small shoe and 60 depression 18 wins thereby, whether he has already won certain other numbers by prior plays or not. If the ball comes to rest in a depression marked "Lose all," the player must begin again at one to count. If it comes to 65 rest in a positive depression, the count is increased by the number of the depression; if in a negative depression, the count is decreased in like manner. The first player who counts five hundred (by one or by several 70 plays) wins. Owing to the up and down grades and to the sidewise inclination of the way 4 skill is required to get the ball through shoe 3 at the desired point and into desired 75 depressions.

Near the open end of shoe 3 is a transverse series of depressions separated by inclined partitions 170, leading from the high part 17 to the lower level of the board in which the depressions are formed. The tops of these 80 partitions are grooved, so that a ball rolling onto either one will be carried by said series of depressions.

I do not limit myself to all the details of the device described, as the parts may be 85 modified somewhat in form and arrangement without departing from my invention.

While body 3 and rim 2 are not shown as integral parts of the board, each being shown as a separate piece secured on or to the board, 90 this is evidently not essential.

I claim—

1. A game-board, a horseshoe-shaped body 3 secured thereon, a surrounding rim also secured to said board, body 3 and the rim forming a way 4 adapted to receive a rolling ball, there being openings for such ball at intervals through the body 3, and suitably-marked 95 depressions, in the board, within the shoe-shaped body 3.

2. A game-board, a horseshoe-shaped body 3 secured thereon, a surrounding rim also se- 100

cured to said board, body 3 and the rim forming a way 4 adapted to receive a rolling ball, there being openings for such ball at intervals through the body 3, and suitably-marked 5 depressions, in the board, within the shoe-shaped body 3, and a central small horseshoe 19 adapted to receive the ball when the latter is properly sent thereto.

3. A game-board, a horseshoe-shaped body 10 3 secured thereon, a surrounding rim also secured to said board, body 3 and the rim forming a way 4 adapted to receive a rolling ball, there being openings for such ball at intervals through the body 3, and suitably-marked 15 depressions, in the board, within the shoe-shaped body 3, and means consisting of a spring, and a small horseshoe 15 operated by the spring and adapted to hold the ball, before each shot, loosely between the sides of 20 the shoe, and when operated to eject the ball at the desired velocity.

4. A game-board, a horseshoe-shaped body 3 secured thereon, a surrounding rim also secured to said board, body 3 and the rim forming 25 a way 4 adapted to receive a rolling ball, there being openings for such ball at intervals through the body 3, and suitably-marked depressions, in the board, within the shoe-shaped body 3, means consisting of a spring, 30 and a small horseshoe 15 operated by the spring and adapted to hold the ball, before each shot, loosely between the sides of the shoe, and when operated to eject the ball at the desired velocity, a handle at the free end 35 of the spring, and a guide for the handle.

5. A game-board, a horseshoe-shaped body 3 secured thereon, a surrounding rim also secured to said board, body 3 and the rim forming a way 4 adapted to receive a rolling ball, 40 there being openings for such ball at intervals through the body 3, and suitably-marked depressions, in the board, within the shoe-shaped body 3, some of the depressions being positive and some negative.

45 6. A game-board, a horseshoe-shaped body 3 secured thereon, a surrounding rim also secured to said board, body 3 and the rim forming a way 4 adapted to receive a rolling ball, there being openings for such ball at intervals through the sides of the horseshoe-shaped 50 body 3, an enlarged opening through said body 3 at the toe end, and an obstruction in the way opposite said opening.

7. A game-board, a horseshoe-shaped body 55 3 secured thereon, a surrounding rim also se-

cured to said board, body 3 and the rim forming a way 4 adapted to receive a rolling ball, there being openings for such ball at intervals through the body 3, and suitably-marked depressions, in the board, within the shoe-shaped body 3, the depressions being arranged 60 in parallel horseshoe-shaped series.

8. A game-board, a horseshoe-shaped body 3 secured thereon, a surrounding rim also secured to said board, body 3 and the rim forming a way 4 adapted to receive a rolling ball, there being openings for such ball at intervals through the body 3, and suitably-marked depressions, in the board, within the shoe-shaped body 3, the depressions being arranged 70 in parallel horseshoe-shaped series, and the transverse series of depressions near the open end of body 3.

9. A game-board, a shoe-shaped body 3 and a substantially parallel rim on the board, the 75 transverse series of depressions near the open ends of the shoe, inclined partitions between the depressions and extending from the high portion 17 to the lower portion of the board in which the depressions are located, the tops 8c of the inclined partitions being concaved, whereby a ball rolling onto either partition will be carried by said transverse series of depressions.

10. A game-board, a horseshoe-shaped body 85 3 secured thereon, a surrounding rim also secured to said board, body 3 and the rim forming a way 4 adapted to receive a rolling ball, there being openings for such ball at intervals through the body 3, and suitably-marked 90 depressions, in the board, within the shoe-shaped body 3, said way having up and down grades, as set forth.

11. A game-board, a horseshoe-shaped body 3 secured thereon, a surrounding rim also secured to said board, body 3 and the rim forming a way 4 adapted to receive a rolling ball, there being openings for such ball at intervals through the body 3, and suitably-marked 95 depressions, in the board, within the shoe-shaped body 3, said way having up and down grades and also an inclination toward the shoe 100 3, as set forth.

In testimony whereof I have signed this specification in the presence of two subscribing witnesses.

CHARLES J. DORSEY.
